UNITED STATES PATENT OFFICE.

JONAS W. AYLSWORTH, OF EAST ORANGE, NEW JERSEY, ASSIGNOR TO HALOGEN PRODUCTS COMPANY, OF GLEN RIDGE, NEW JERSEY, A CORPORATION OF NEW JERSEY.

PROCESS AND APPARATUS FOR COMPRESSING, DRYING, AND TRANSFERRING CHLORIN GAS.

1,134,432.

Specification of Letters Patent.

Patented Apr. 6, 1915.

Application filed November 6, 1913, Serial No. 799,530. Renewed September 2, 1914. Serial No. 859,906.

To all whom it may concern:

Be it known that I, JONAS W. AYLSWORTH, a citizen of the United States, and residing in East Orange, in the county of 5 Essex and State of New Jersey, have invented certain new and useful Improvements in Processes and Apparatus for Compressing, Drying, and Transferring Chlorin Gas, of which the following is a description.

10 My invention relates to an improved process for continuously transferring gases such as chlorin and bromin, and to improved apparatus by which such process may efficiently be carried out.

15 The object of my invention is to provide an improved process and apparatus for this purpose in which the gas is effectively dried during the process and is compressed under substantially uniform pressure, and a supply thereof is maintained under pressure, available for withdrawal and use.

20 It is particularly important in many industrial applications that chlorin gas may be supplied in dry condition and at a desired pressure. Moisture in chlorin or 25 bromin gas greatly impairs its usefulness, because, chiefly, of the corrosive action of the wet gas on pipes, etc., which is not encountered in the case of dry gas. Chlorin

30 is the gas chiefly considered herein, as the element to be handled by my invention, but as the behavior of bromin is very similar, it will be understood that what is stated herein as to chlorin applies as well to 35 bromin.

Chlorin as commercially produced usually contains water, and it must be dried, according to the usual practice, by a special drying process, before it can be used. As 40 stated, one of the features of my invention is that the chlorin is dried during its transfer and compression. The improved process is a continuous one, makes no use of valves or like moving parts, and is capable 45 of maintaining and supplying chlorin gas under a considerable and substantially constant pressure. It may effectively be used, for example, for measuring and delivering chlorin under pressure to the chlorinating 50 chambers in a process for making chloronaphthalenes, and the like, disclosed in my Patent No. 914,223, dated March 2, 1908, and for all other uses in which chlorin is to

be transferred, dried, and supplied under more or less pressure.

The invention is founded on my appreciation of the practically unique properties of sulfuric acid as an agent for causing the transfer, drying and compressing of chlorin gas in a process such as will be described. 55 In the process a chamber is partly filled with sulfuric acid the remainder of the chamber above the acid being filled with chlorin gas, which is supplied thereto. A helical pipe coil or coils are mounted in 60 this chamber to rotate therein and alternately entrap volumes of chlorin and H_2SO_4 , and deliver the same continuously to a receiving chamber, in which the acid is separated from the gas and returned to 65 the first chamber. The acid being much heavier than the gas will act like a series of pistons on the alternate volumes of gas in the coils to compress the same in a regulable manner, and transfer the same continuously to the receiving chamber. At the 70 same time the sulfuric acid, since it comes into intimate contact with the chlorin gas at all stages of the process, splashing over and covering the various pipe and chamber 75 surfaces, forms a very efficient drying agent for the chlorin.

I am aware that rotary pumping apparatus having a general similarity to that referred to has been proposed for pumping 80 water or for forcing or compressing air, water generally being the fluid used to act as a piston to drive the air through the spiral tubes to the point of discharge. Such a process, however, could not be used practically for transferring chlorin, because of the absorption of the latter by the water, and because of the corrosive action of the wet chlorin. The same objection holds as to other fluids, and so far as I am aware 85 sulfuric acid is the only agent which can be practically used in such a process as mine for transferring and compressing chlorin which will not mix or react with or be materially affected by the chlorin, and at the same time will dry the gas. It should also 90 be noted that sulfuric acid, being much heavier than water, gives greater pressure than water for the same dimensions of helix, depth of liquid, etc., and that therefore a 95 more compact apparatus may be used. Be-

cause of the use of the H_2SO_4 and the chlorin the apparatus which I use in practice for carrying out my process is made of cast or wrought iron, although other substances such as nickel alloys, not easily corroded by chlorin, might be used.

An improvement also resides in my improved preferred apparatus, in the means for returning acid from the receiving chamber to the pump chamber which does away with the use of a valve, which latter is objectionable where sulfuric acid is under consideration.

In order that my invention may be more clearly understood, attention is directed to the accompanying drawings forming a part of this specification, in which the same reference characters are used to designate corresponding parts throughout and in which—

20 Figure 1 is a central longitudinal sectional view, parts being shown in elevation, of an apparatus constructed in accordance with my invention and forming a suitable means for carrying out my improved process. 25 Fig. 2 is a front elevation, partly in section, showing a modified form of the pumping element of the apparatus shown in Fig. 1, and Fig. 3 is an end elevation of Fig. 2 looking from the left.

30 Referring especially to Fig. 1, reference character 1 represents a closed chamber provided with a chlorin supply pipe 2, and 3 represents a closed chamber into which the chlorin is adapted to be transferred from chamber 1 by a pumping means 4. Chamber 1 is mounted on a suitable base 5 and chamber 3 is mounted, preferably at the same level as chamber 1, on suitable supports 6. In one wall of chamber 1 is journaled a driving shaft 7 which extends outwardly through a stuffing box 8 provided with suitable packing 9, preferably of graphite. Shaft 7 is driven by any suitable means, such as worm gearing 10, at a uniform speed. The pumping means 4 preferably comprises a pumping element consisting of a helical pipe coil 11 one end portion 12 of which opens into chamber 1 and the other end portion 13 of which extends radially of the coil, and is suitably connected to a hollow axial hub portion 14 which in turn is connected to one end of a pipe 15, in axial alinement with shaft 7. Pipe 15 preferably extends through a stuffing box 8' similar in construction to the stuffing box 8, but located in the opposite wall of chamber 1. A spider 16 serves as a support for the coil 11. Hub 17 of spider 16, and also hub portion 14 have a splined connection 18 with shaft 7. The other end of pipe 15 is journaled in one wall of chamber 3, leakage being prevented by a stuffing box 19 provided with suitable packing 20, preferably of graphite, and this end opens into a downwardly directed discharge spout 21 secured

to the interior of chamber 3. Chambers 1 and 3 are partially filled with sulfuric acid 22, which is heavier than the gas to be pumped and during the operation of the device the acid 22 is maintained, so long as the pressure in chamber 3 remains approximately the same, approximately at levels A and B respectively, as hereinafter described. Communication between the lower portions of chambers 1 and 2 is established by suitable means whereby excess sulfuric acid in chamber 3 may be returned to chamber 1.

The preferred means for connecting the lower portions of chambers 1 and 3 comprises the long vertical U-tube 23 as shown, provided with a draw-off cock 24, if desired. The tube 23 should be of a good diameter and the length of each vertical arm thereof should be sufficient so that the acid therein will counterbalance the pressure in the receiving chamber 3. With this arrangement the level of acid in chamber 3 or the vertical arm of the tube 23 connecting therewith, will depend on the pressure of chlorin gas therein. In place of the above described construction a by-pass between the bottoms of the two chambers governed by a float valve in chamber 3 may be used, as shown in dotted lines, to keep the level in chamber 3 at about level B', acid flowing back to chamber 1 as pistons of acid are discharged into the top of chamber 3 from the pump. The construction shown with the long vertical tube is preferred, however, since it does away with the necessity of a valve which is constantly covered with sulfuric acid. Further, the preferred construction affords a more uniform regulation of the pressure in chamber 3, since, if gas is not withdrawn regularly therefrom, and the pressure rises, the acid level will drop below level B, and a greater space will be afforded for the gas. In practice the compressed gas will be withdrawn from chamber 3 for use quite continuously during the continuance of the process.

In the preferred construction illustrated the length of the vertical arm of pipe 23 connected with chamber 3 must be long enough so that the pressure in chamber 3 will never force the level B of the acid in pipe 23 beyond the bend at the bottom of the pipe, as in that case the seal would be broken and gas would rise through the acid in the arm of the pipe connected with chamber 1, and return to chamber 1. Thus, if it be assumed that the pressure at which the gas is delivered by the coils 4 to the chamber 3 shall be five pounds, and the specific gravity of the sulfuric acid used to be approximately 1.8, the excess of pressure in chamber 3 above that in chamber 1, namely a maximum of 5 pounds, would correspond to a column of H_2SO_4 approximately 6 feet high, and accordingly the vertical arm of

pipe 23 should be somewhat more than six feet long.

In the construction illustrated a pipe 25 opening into chamber 3, near the top thereof, serves to conduct the transferred chlorin from chamber 3. Apertures 26 are provided in the top and bottom of each of the chambers 1 and 3 through which the acid may be supplied to and drawn from the chambers 10 when desired, these apertures being suitably closed as by plugs when the apparatus is in use. The top of chamber 3 is formed as a cover 27 which preferably is provided with a flange 28 adapted to seat in a groove 29 formed in the top edge of the vertical walls of the chamber, a suitable packing 30, preferably of graphite, being provided to seal the cover. This cover may be held in position by any suitable means, not shown.

20 In Figs. 2 and 3 the pumping element is shown as a pair of pipe coils 11', 11', formed in a double helix, one end portion 12' of each coil 11' opening into supply chamber 1 at diametrically opposite points, and the 25 opposite end portion 13' of each coil extending radially of the coil from diametrically opposite points and being suitably connected to the hollow hub portion 14'. Hollow hub portion 14' is connected to pipe 15 30 and splined to shaft 7 in the same manner as hub portion 14 of the device shown in Fig. 1. A partition 31 is provided centrally of the hollow hub portion 14' and pipe 15 to insure all the fluid discharged through 35 portions 13', 13', of the two coils 11', 11', entering pipe 15.

The operation of the apparatus shown in Fig. 1 is as follows:—Chambers 1 and 3 being supplied with the proper amount of concentrated sulfuric acid and the apertures 26 being closed, chlorin is supplied, preferably at atmospheric pressure, to the upper portion of chamber 1 through pipe 2 from any suitable source, and shaft 7 is driven at a suitable uniform speed through worm gearing 10 from any suitable source of power, not shown. The rotation of shaft 7 actuates pumping element 4, and the open end portion 12 thereof will alternately be immersed 45 in the chlorin and H_2SO_4 whereby alternate pistons of chlorin and sulphuric acid will be entrapped in the coil 11. The helical pipe coil operates somewhat on the principle of the screw of Archimedes, the heavier 50 fluid, or H_2SO_4 , tending by gravity to occupy the lower segments of the helix. The continuous entrapping of further portions of chlorin and H_2SO_4 will force the previously entrapped chlorin and H_2SO_4 55 through the coil in a helical path to the tube 15 to thereby cause the discharge of alternate volumes of chlorin and H_2SO_4 through spout 21 into chamber 3, the chlorin being compressed by the action of the H_2SO_4 pistons while passing through the coil. The

degree of compression of the chlorin may be regulated by the length of the helical coil, and by the speed at which it is driven, as well as by the depth of the H_2SO_4 in chamber 1, these being preferably regulated so as to maintain the chlorin in chamber 3 at a pressure of five or more pounds above atmospheric pressure, which is found most desirable for carrying out the process described in my Patent No. 914,923 referred to. This 75 pressure in chamber 3 will cause the transfer of some of the acid from chamber 3 through pipe 23 to chamber 1 and as long as the device is in operation the acid will be maintained in chambers 1 and 3 approximately at levels A and B respectively, or at such levels as will be maintained by the excess of pressure of chlorin gas in chamber 3 over that in chamber 1, for, as the pistons of H_2SO_4 are discharged into 80 chamber 3, the pressure therein will force the surplus H_2SO_4 through pipe 23 into chamber 1 until the H_2SO_4 in chamber 3 is again at level B, or at whatever level corresponds to the difference in pressure between 85 the chambers.

The upper portion of chamber 3, from which the compressed chlorin is conveyed to the point of application by pipe 25, serves as a storage chamber or reservoir whereby 90 wide fluctuations of pressure at the point of application are prevented.

The operation of the apparatus when provided with the modified pumping element disclosed in Figs. 2 and 3 is the same as 100 above described except that for each revolution of shaft 7 two pistons each of H_2SO_4 and chlorin are entrapped instead of one whereby the discharge into chamber 3 is more nearly continuous and the liability of 105 fluctuations in pressure of the chlorin gas in chamber 3 and in the levels of the H_2SO_4 in chambers 1 and 3 is lessened.

Having now described my invention, what I claim and desire to protect by Letters Patent is:—

1. The process of transferring, compressing and drying chlorin gas which consists in entrapping volumes of the chlorin gas between alternate volumes of sulfuric acid, forcing the entrapped alternate volumes continuously through an inclosed path to a desired point, causing intimate contact between the acid and the gas and thereby drying the latter, and permitting the separation of the acid from the dried gas, substantially as described.

2. The process of transferring, compressing and drying chlorin gas which consists in causing alternate volumes of chlorin gas and sulfuric acid to continuously enter a helical pipe, rotating the latter and thus transferring the acid and gas compressed thereby into a receiver, causing intimate contact between the acid and gas therein and thereby 125 130

drying the gas, and separating the acid from the dried gas, substantially as described.

3. The process of transferring, compressing and drying chlorin gas which consists in 5 entrapping alternate pistons of the chlorin gas and sulfuric acid at a point of low pressure, in forcing the entrapped volumes of gas and acid in a helical path continuously in the same direction, while compressing the 10 pistons of gas by the action thereon of the pistons of liquid, to a point of higher pressure, causing intimate contact between the acid and gas to dry the latter, and returning the acid from the point of high pressure to 15 the point of low pressure, substantially as described.

4. In an apparatus for transferring, compressing and drying chlorin, the combination of a chamber partially filled with sulfuric acid and adapted to be supplied with 20 chlorin gas, a second chamber, and means comprising a continuously rotating helical pipe coil having one end opening into said first chamber and its other end communicat-

ing with said second chamber, whereby alternate volumes of the acid and chlorin gas are entrapped from said first chamber, discharged into said second chamber, the gas being under pressure, the gas dried by contact with the acid, and the acid separated 25 from the gas in said second chamber, and a vertically positioned U-shaped pipe mounted below said chambers with its ends respectively opening into the lower portions of each of the same for returning acid from 30 said second to said first chamber, the vertical height of said pipe being sufficient so that the maximum pressure in said second chamber shall not force the level of the acid in said pipe beyond the bend in the same, 35 substantially as described.

This specification signed and witnessed this 3d day of November 1913.

JONAS W. AYLSWORTH.
